Primary Examiner—Caron D. Veynar**CLAIM**

The ornamental design for a restaurant ordering unit, as shown and described.

DESCRIPTION

FIG. 1 is a front elevational view of the restaurant ordering unit of the present invention;

FIG. 2 is a rear elevational view of the restaurant ordering unit of FIG. 1;

FIG. 3 is a left side elevational view of the restaurant ordering unit of FIG. 1;

FIG. 4 is a right side elevational view of the restaurant ordering unit of FIG. 1;

FIG. 5 is a top plan view of the restaurant ordering unit of FIG. 1; and,

FIG. 6 is a bottom plan view of the restaurant ordering unit of FIG. 1.

The broken lines showing of letters in FIG. 1 is for illustrative purposes only and form no part of the claimed design. The electrical cord in FIGS. 3-6 shown broken away to indicate indeterminate length.
